UNITED STATES PATENT OFFICE.

JOHN LE TUAL, OF MONTREAL, QUEBEC, CANADA.

MACHINE FOR REMOVING SNOW FROM ROADWAYS.

1,410,582.

Specification of Letters Patent. Patented Mar. 28, 1922.

Application filed March 20, 1920. Serial No. 367,340.

To all whom it may concern:

Be it known that I, JOHN LE TUAL, a subject of the King of Great Britain, residing at Montreal, Province of Quebec, Canada, have invented certain new and useful Improvements in Machines for Removing Snow from Roadways; and I do hereby declare that the following is a full, clear, and exact description of the invention, such as will 10 enable others skilled in the art to which it appertains to make and use the same.

The present invention relates to a new and improved machine for the removal of snow from roadways and subsequently delivering 15 the same into a vehicle moving in unison with the machine.

The principal object of the invention is to provide an apparatus for the automatic removal of the snow from roadways, streets, 20 or the like and having conveying means for the disposal of the same into vehicles.

Another object of the invention is to provide an apparatus of the character described, wherein the cutting elements and conveying 25 frame are adjustable with respect to the road bed.

With the above and other objects in view which will hereinafter appear as the description continues, the invention consists of 30 the novel features of construction, combination and formation of parts as will be herein-after more fully described and particularly pointed out in the appended claims.

In the accompanying drawings has been 35 shown a simple and preferred form of the invention, it being however understood that no limitation is necessarily made to the precise structural details herein exhibited, but the right is hereby reserved to any changes, 40 alterations or modifications to which recourse may be had that come within the scope of the claims without departing from the spirit of the invention or sacrificing the efficiency of the same.

45 Figure 1 is a perspective view of the improved apparatus for the removal of snow;

Figure 2 is a top plan view of the apparatus here;

Figure 3 is a side elevation of the apparatus, a part of the casing being broken away to expose the conveyor and adjusting element therefor;

Figure 4 is a detail elevation of the steering mechanism; and,

50 Figure 5 is a fragmental section of a part of the conveyor belt.

In apparatus for collecting and removing snow, hitherto devised it has been customary to provide rotary plow elements mounted on a wheel supported frame and adapted to be forced into a mass of snow, or to pass over the road surface and cut the pack and throw the same aside by centrifugal force.

It is the purpose of the invention to support the frame 10 upon the sled member 11, 65 which latter is provided with runners 12. A bolt 13 connects the frame 10 with the sled member 11 by which means the said frame has pivotal connection with the said sled. 70

A conveyor frame 14, comprising the metallic side wall plates 15 and 16 is disposed in an incline plane and its upper end, namely the rear part thereof, is supported by the frame 10, upon sled 11. The forward 75 part of the conveyor frame 14 adjacent the extreme end has a shaft 17 extending transversely therethrough, on the outer ends of which are mounted the star wheels 18 and 19 and which support the apparatus at this 80 point. These star wheels 18 and 19 are formed with the contact points 20 which bite into the roadway surface whereby traction for the apparatus is obtained.

Likewise the shafts 21 and 22 are mounted 85 in the extreme ends of the conveyor frame plates 15 and 16 and carry the rollers 23 and 24.

Disposed within the conveyor frame 14 on the shafts 21 and 22 are the sprockets 25, 26, 90 27 and 28.

The shaft 22 has its ends extending outwardly beyond the side walls 15 and 16 of the frame 14. Keyed to said shaft ends are the gears 29 and 30 which mesh with relatively large gears 31 and 32 on the shaft 17 adjacent the star wheels 18 and 19. An apron comprising an endless wire screen 33 passes over rollers 23 and 24 and extends the entire length of the conveyor frame 14. 100

Motion is imparted to the conveyor apron 33, by the chains 34 and 35, which are trained over the gears 26 and 29, and 25 and 28 respectively.

A rod 36 is secured to the lower end portions of the side walls 15 and 16. Hingedly mounted on said rod 36 is a cutting plate 37 provided on its outer edge with a series, of teeth or serrations.

This cutting plate 37 is adjustable on rod 110 36 by means of the tangent bar 39 the upper end of which is formed with a rack 40 and

the rack end of said bar 39 passes through a strap member 41 mounted on the side wall 15 of the conveyor frame 14. This strap member 41 may be provided with teeth to engage 5 the rack 40 of bar 39, whereby the cutting plate 37 may be adjusted to regulate the plane of the cutting teeth 39 with respect to the snow to be cut.

Likewise a vertically disposed plate 42 10 is suitably connected to the side wall 16 of the conveyor frame 14 and is formed with cutting teeth 43 disposed at right angle to the teeth 38 of cutting plate 37.

The function of plate 37 is to cut the 15 surface snow from the roadbed, while that of plate 42 is to cut into the heavier accumulations or drifts.

A downwardly directed chute 44 is connected to the upper end of the conveyor casing 14 the function of which will be later described.

A plurality of wire cables 45 extend longitudinally of the apron screen 33 and pass over the transverse wire members 46 on 25 which are mounted in staggered relation the hooks 47 and the triangular studs 48.

The hooks 47 and studs 48 form with the screen 33, the conveyor proper and as the apparatus is drawn by animals suitably 30 hitched to the draft, not illustrated, the teeth 38 of the cutting plate 37 will bite into the surface snow. This snow when severed will be forced rearwardly upon the conveyor apron and as the star wheels 19 and 20 are 35 revolved by contact with the cross surface, the gears 31 and 32 on shaft 17, will actuate gears 28 and 29 on shaft 22. In this manner gears 27 and 29 on shaft 22 will be likewise 40 actuated and in turn rollers 23 and 24 will impart movement to the conveyor screens 33.

As the snow accumulates upon the lower end of the conveyor screen 33, it is held thereon by the hooks 47 and studs 48 and elevated with said screen and finally deposited 45 into the chute 44. The chute 44 is disposed downwardly and outwardly from the conveyor casing 14 and is formed with relatively vertical walls 58 and 59 and a divergent wall 60. These walls 58 and 59 50 together with the base portion 61 guide the snow downwardly out of the mouth 49 of the chute and the snow drops by gravity into a vehicle arranged alongside of the apparatus.

55 For elevating the conveyor casing 14, I secure by bolts 50 the rack bars 51 to each side of the frame 10, while in the sled member 11 is mounted a shaft 52 carrying a gear 53. Said shaft has its ends bent in such

60 manner as to form the crank handles 54 and

when said handles 54 are actuated the gears 53 engage racks 51 serving to raise or lower the upper part of frame 10 and conveyor casing 14 in its entirety. A pawl 55 is pivotally connected to the sled member 11 65 and serves when in engagement with the teeth of gear 53, to hold the frame 10 and casing 14 in adjusted position.

The apparatus is guided by means of a hand wheel 55 mounted on shaft 56, which 70 latter has bearings in the bracket 57. A cable is wound around shaft 56 and passes over a pulley, not illustrated on the conveyor casing 14 and its opposite end is connected to one of the runners 12. 75

The cutting plate 42 may likewise be capable of adjustment by means of the link connections 62 the ends of which are adapted to be inserted into the openings in the plates 58 connected to the side walls 15 and 16 of 80 the conveyor casing 14.

It is obvious that the apparatus may be handled by a tractor or truck and is adapted for use in connection with the removal of snow from streets, roadways, sidewalks and 85 the like.

Having thus fully described my invention, what I claim as new and desire to secure by Letters Patent is:—

1. The herein described apparatus comprising a sled, a frame member pivotally mounted thereon, a gear carried by the sled, a crank for rotating the gear, and a rack carried by the frame member, and meshing with the gear, a conveyor carried by the 90 frame, a blade at the lower edge of said conveyor, and side blades at the opposite sides of the conveyor, substantially as and for the purposes set forth.

2. The herein described apparatus comprising a sled, a frame pivotally connected to said sled, a rack carried by the frame and extending beyond the sides of the sled, a gear journaled upon the sled and meshing with the rack, means for rotating said gear, 95 a conveyor carried by the frame, a chute at one end of the conveyor, a fly-wheel carried by the frame for driving the conveyor, a blade adjustably connected at the forward 100 end of the conveyor, and disposed in a substantially horizontal plane, means for tilting said blade, and a vertical plate attached to one end of said conveyor and cooperating with the blade, and means for swinging the conveyor upon the sled, substantially as 110 and for the purposes set forth.

In witness whereof I have hereunto set my hand.

JOHN LE TUAL.
